OIL BURNER

Charles E. Goulding, Sr., Tampa, Fla.

Application June 8, 1938, Serial No. 212,586

1 Claim. (Cl. 158—91)

This invention relates to oil burners and has for an object to provide an oil burner in which two separate and distinct sets or pairs of horizontal air drafts enter the burner at different levels and at right angles to each other to promote a more intense flame with less fuel consumption than conventional burners having a vertical center draft.

A further object is to provide a burner of this type which will be formed of a few strong simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification,

Figure 1 is a plan view of an oil burner constructed in accordance with the invention.

Figure 2 is a cross sectional view of a burner taken on the line 2—2 of Figure 1.

Figure 3 is a cross sectional view of the burner taken on the line 3—3 of Figure 2.

Figure 4 is a cross sectional view of the burner taken on the line 4—4 of Figure 3.

Referring now to the drawing in which like characters of reference designate similar parts in the various views, 10 designates the cylindrical body of the burner the same having a shallow inverted cone-shaped bottom 11. The bottom of the body has attached thereto an axially disposed depending tube 12. A flanged bushing 13 is threadedly engaged with an annular collar 14 which projects from the inner surface of the tube. The body is provided at the top with a flange 15. A tube 16 is secured at the lower end in the bushing 13 and extends upwardly in the body to a height slightly above the bottom 11 of the body. A fuel pipe 17 enters the body tube 12 and directs the fuel into the space between the body tube and the central tube 16.

The body 10 is provided with preferably three rows of radially disposed openings 18 located above the median diameter of the body. These openings admit an air draft horizontally into the body.

The air draft is divided and directed by baffles each comprising a vertical wall 19 extending transversely of the body, and an inclined wall 20

at the top of the vertical wall. The inclined wall extends from just below the draft openings 18 to the top of the body.

The vertical walls 19 of the baffles are spaced a predetermined distance apart by spacing bars 21 which extend across the bottom of the walls near the ends thereof and are secured to the bottom 11 of the body by vertically disposed brackets 22 which rise from the bottom 11 of the body. The vertical walls of the baffles form a rectangular space extending across the body below the draft openings 18. The inclined walls 20 of the baffles divide the draft openings into four sections or divisions, two of which admit air from opposite sides of the burner underneath the baffles at one level while the other two admit air from opposite sides of the burner above the baffles at a higher level, as best shown in Figure 3. The opposing drafts which enter the burner above the baffles are disposed at right angles to the opposing drafts which enter the burner below the baffles.

A substantially Y-shaped baffle 23 is interposed between the vertical walls 19 and is secured to and extends transversely to the walls at the center thereof, as best shown in Figures 2 and 4. The baffle is secured to the center tube 16 through the medium of a tongue 24, best shown in Figure 3. The top of the center tube 16 extends to the plane of the lower edges of the vertical walls 19 which latter are spaced above the bottom 11 of the body 10 through the medium of the brackets 22.

The Y-shaped baffle 23 provides the rectangular space formed by the vertical walls 19 of the baffle carried by the body, into two equal spaces, and the curved branches of the Y-shaped baffle effect a gradual reduction of area of the spaces as the branches approach the top of the vertical walls 19.

In operation fuel enters the generating space between the tubes 12 and 16 through the pipe 17. In this space the fuel is vaporized and ignited. It is then caught between the draft streams entering underneath the vertical walls 19 of the baffle carried by the body. As the ignited fuel passes up between said vertical walls it is divided by the Y-shaped baffle 23 and the branches of the Y-shaped baffle force it out against the draft streams which enter the burner through the draft openings 18 above the inclined walls 20 of the baffle carried by the body 10. This top draft forces the two flames together above the Y-shaped baffle and spreads out the flame in a single fan shaped flame of great intensity.

The baffle walls 19 and 20 are cooled and kept from burning by the draft rising from beneath the vertical walls 19. The Y-shaped baffle is cooled and kept from burning by the draft entering the center tube 16.

From the above description it is thought that the construction and operation of the invention will be fully understood without further explanation.

10 What is claimed is:

An oil burner comprising a cylindrical body, a tube depending from the body, a bushing in the tube, a tube disposed axially in the first named tube and open at both ends, a fuel pipe 15 entering the first named tube, a pair of vertically disposed spaced baffle walls in the body, inclined baffle walls rising from the top of the vertical baffle walls and extending to the inner sur-

face of the body, there being a plurality of rows of draft openings arranged in the body above the top of the vertical baffle walls, said vertical baffle walls being spaced from the bottom of the body, said inclined baffle walls dividing the draft openings into four sections two of which admit air from opposite sides of the body underneath the inclined baffle walls and underneath the vertical baffle walls while the other two admit air from opposite sides of the body above the inclined baffle walls to impinge against the draft rising between the vertical baffle walls at a right angle and form a fan shaped flame, and a baffle disposed between and connecting said vertical baffle walls for spreading flame outwardly toward the ends of the vertical baffle walls.
